UNITED STATES PATENT OFFICE.

GERRY JONES, OF BINGHAMTON, NEW YORK, ASSIGNOR TO EDWARD F. JONES, OF BINGHAMTON, NEW YORK.

REINFORCED-CONCRETE PIT FOR WAGON-SCALES.

971,758.

Specification of Letters Patent.

Patented Oct. 4, 1910.

Application filed November 2, 1908. Serial No. 460,751.

To all whom it may concern:

Be it known that I, GERRY JONES, of Binghamton, in the county of Broome, in the State of New York, have invented new and useful Improvements in Reinforced-Concrete Pits for Wagon-Scales, of which the following, taken in connection with the accompanying drawings, is a full, clear, and exact description.

This invention relates to certain improvements in reinforced concrete pits for wagon scales, the primary object of which is to incorporate in the concrete effective anchorages for the ends of the platform supporting lever and at the same time to tie these anchorages together by suitable angle irons which also serve as a reinforcing frame for the upper inner edges of the concrete adjacent to the platform to prevent crumbling or excessive mutilation of this part of the concrete pit by the wheels of the vehicle in traveling to and from the platform. In other words, I have sought to produce a reinforced concrete pit with as little metal as may be practicable to preserve the durability of the pit and still afford a suitable anchorage for the platform supporting levers thereby producing a complete pit at a minimum cost.

Other objects and uses relating to specific parts of my invention will be brought out in the following description.

In the drawings—Figure 1 is a perspective view of a reinforced concrete pit embodying the various features of my invention. Fig. 2 is an enlarged perspective view of one corner of the pit showing one of the corner plates and adjacent ends of the angle irons and by which the corner plates are tied to each other, this view also showing a portion of one of the platform supporting levers as operatively connected to one of the anchor plates. Fig. 3 is a diagonal sectional view through one of the corners of the pit showing the parts seen in Fig. 2. Fig. 4 is a sectional view diagonally across one of the corners of the pit and corner bracket through the anchor plate and clevis and adjacent end of the platform supporting lever. Figs. 5 and 6 are perspective views respectively of the corner bracket and anchor plate.

This reinforced concrete pit comprises essentially an open rectangular concrete

frame —1— which is built up in suitable forms in the ground previously prepared therefor and incorporated in each corner of the concrete are angular brackets —2— which are connected by angle irons —3— running along the upper inner corners of the concrete frame —1— thereby forming a rectangular metal frame which is embedded in the concrete.

The brackets —2— each consist of upright side plates —4— united to each other at substantially right angles, and horizontal flanges —5— formed integral with the upper ends of the side plates —4— and also united to each other at right angles forming an upright annular bracket having outwardly projecting flanges integral with its upper end.

The plates —4— are embedded in the inner faces of the corner of the concrete frame —1— with their inner faces substantially flush with the inner faces of said concrete frame and their lower ends provided with recesses —6— extending upwardly therefrom in which the concrete is filled to offer additional resistance to accidental displacement of the plates from the concrete.

The flanges —5— on the upper end of the bracket —2— are embedded in the upper faces of the concrete frame —1— with their upper faces substantially flush with those of the concrete wall thereby tying the sides and ends of said wall together at their meeting ends and affording an effective anchorage for supporting the platform levers as —a—.

The upper inner corners of each bracket —2— are formed with vertical and horizontal rabbets —7— and —8— of sufficient depth to receive the adjacent ends of the angle irons —3— which are bolted to the brackets —2— thereby tying them together and extending from end to end and side to side of the concrete frame —1— and forming reinforcing corners at the upper inner edges of the concrete wall to prevent mutilation of this part of the wall by the vehicle driving to and from the platform, not shown. These angle irons are flush with the upper and inner faces of the concrete wall thereby giving a neat and trim appearance to the reinforced concrete pit and also serving to tie the corner pieces together and

at the same time adding to the tensile strength of this part of the concrete wall to prevent spreading thereof under the strains to which it may be subjected by 5 loaded vehicles passing to and from the platform.

The plates —4— are provided on their inner faces between their upper and lower ends with inwardly projecting flanges —9— 10 forming convenient supports or seats for anchor plates —10— which rest upon said flanges and tend to brace the side plates —4— and adjacent ends of the concrete wall against inward pressure, each of said 15 plates being provided at its ends with recesses —11— which interlock with suitable shoulders or ribs —12— rising from the flanges —9—. The central portion of each plate is provided with vertical openings 20 —13— enlarged at its upper end for the reception of a pin —14—, the latter being passed through and serves as a convenient support for an open link or clevis —15— which extends some distance downwardly 25 from its supporting pin —14— and forms a convenient swinging support for the adjacent end of the platform lever —4—, the latter being provided with a knife bearing —16— upon which the platform is supported.

Each corner of the concrete rectangular wall is reinforced by one of the brackets —2—; each bracket is provided with an anchor plate —10— and each anchor plate 35 supports a clevis —15— which in turn supports one end of a platform supporting lever and although I have shown only one of these levers, it is to be understood that each corner bracket is utilized for supporting 40 one end of a similar lever and also serves to tie the adjacent ends of the sides and ends of the concrete wall together while the angle irons —3— serve to tie the corner brackets together and protect the upper inner ends of 45 the corners against mutilation by the traveling of vehicles to and from the platform of the scales.

What I claim is:

1. In a reinforced concrete pit for wagon scales, an open concrete frame, a metal frame running around and resting upon the top face of the concrete frame, said metal framing extending some distance below the top and bearing against the inner face of 50 said concrete frame, angular corner brackets fitting in the inner corners of the concrete frame and secured to the corresponding corners of the metal frame, clevises secured on said brackets, and levers connected to said clevises.

2. In a reinforced concrete pit for wagon scales, a concrete inclosing wall forming the 55 pit, upright corner brackets angular in cross

section seated in the inner corners of the concrete wall and having horizontal flanges 65 resting upon the top face of said wall, clevises mounted on said brackets, and levers connected to said clevises.

3. In a reinforced concrete pit for wagon scales, a concrete inclosing wall forming the 70 pit, upright corner brackets angular in cross section seated in the inner corners of the concrete wall and having horizontal flanges 75 resting upon the top face of said wall, clevises mounted on said brackets, levers connected to said clevises, and a metal frame angular in cross section resting against the top and inner sides of the upper corners of the concrete wall and secured to the corner brackets. 80

4. A reinforced concrete pit for wagon scales, comprising a rectangular wall, upright metal corner brackets angular in cross section and seated against the inner faces 85 of the corners of the wall, said brackets having their upper ends provided with laterally projecting flanges resting upon the top face of said wall and anchor plates mounted on the brackets at the inner sides thereof and between their upper and lower ends. 90

5. In a reinforced concrete pit for wagon scales, a concrete inclosing wall forming the pit, upright corner brackets angular in cross section and having their sides embedded in the inner faces of the corners of the wall, 95 said brackets being provided with laterally projecting flanges resting upon the top face of the wall, the upright sides of each bracket being provided with inwardly projecting flanges, and anchor plates, one for each 100 bracket, resting upon said flanges.

6. In a reinforced concrete pit for wagon scales, a concrete inclosing wall forming the pit, upright corner brackets angular in cross section and seated in the inner corners of the concrete wall and having their upper ends provided with laterally projecting flanges resting upon the top face of the wall, a metal frame running around and resting upon the inner corners of the wall and secured to the corner brackets, and anchor plates supported upon the brackets in a plane below the metal frame. 110

7. In a reinforced concrete pit for wagon scales, a concrete inclosing wall forming the 115 pit, corner brackets angular in cross section and having their sides seated in the inner corners of the concrete wall and having their upper ends provided with laterally projecting flanges resting upon the top face 120 of the wall each bracket having an inwardly projecting horizontal anchor plate between its upper and lower ends.

8. In a reinforced concrete pit for wagon scales, a concrete inclosing wall forming the 125 pit, upright corner brackets angular in

cross section and having their sides embedded in the inner faces of the corner of the wall and provided with inwardly projecting flanges and shoulders rising from said flanges the upper ends of said brackets being provided with laterally projecting flanges resting upon the top face of the wall.

In witness whereof I have hereunto set my hand this 29th day of October 1908.

GERRY JONES.
